UNITED STATES PATENT OFFICE.

JOHN W. GURLEY, OF INDIANAPOLIS, INDIANA.

SLIVER-HANDLING DEVICE.

Application filed February 6, 1922. Serial No. 534,445.

To all whom it may concern:

Be it known that I, JOHN W. GURLEY, a citizen of the United States, residing at Indianapolis, in the county of Marion and State of Indiana, have invented a new and useful Sliver-Handling Device, of which the following is a specification.

In the manufacture of twine, the sisal or manila is first made into a sliver on a 10 spreader and then drawn into successively finer slivers by being passed successively through other spreaders, draw frames, and finishers until a sliver of the desired fineness is obtained. Heretofore the sliver as it 15 came from each of these machines has ordinarily been coiled by hand in a can, the coiling of the sliver in the can requiring considerable skill; and the cans with the coiled sliver within them have been carried from 20 one machine to another, and used as feed cans over the edge of which the sliver was drawn when fed into the next succeeding machine. This scheme has not only required a great deal of skilled labor, but has 25 been disadvantageous also because of the difficulty of getting the sliver out of the can either for feeding or for other reasons, and because of the cutting or tearing of the sliver as it passed over the edge of the can.

It is the object of my present invention 30 to coil the sliver automatically in a can, thus eliminating the necessity for the skilled labor heretofore required for coiling it; and to coil it in such a way in the can, and to 35 make the can of such construction, that the coiled sliver may be removed laterally from the can and dragged independently of the can from one machine to another; so that the number of cans is reduced, one can to a 40 machine being sufficient, and the difficulties involved in removing the sliver from the can are overcome.

The accompanying drawings illustrate my invention: Fig. 1 is a perspective view of 45 a can and sliver-feeding mechanism embodying my invention, in connection with a draw-frame which is shown in dotted lines; Fig. 2 is a plan of the can and sliver-feeding mechanism which feeds sliver thereinto, with a fragment of the associated draw 50 frame; Fig. 3 is a side elevation, in partial section, of the swinging feed chute; Fig. 4 is a section on the line 4—4 of Fig. 2; Fig. 5 is a section on the line 5—5 of Fig. 2; Fig. 55 6 is a vertical section of the pivotal mounting on the sliver-receiving can; and Fig. 7

is a plan of the can proper, showing the can open in full lines and closed in dotted lines.

The draw frame 9 shown in dotted lines in Fig. 1 may be of any suitable construction, and is merely representative of the various sliver-treating machines, such as spreaders, draw frames, and finishers, with any of which my invention may be associated. From any of these machines, which takes the sliver and draws and works it into a finer sliver in a well-understood manner, such finer sliver 10 is discharged at the end of the machine, the sliver as it is discharged passing between two grooved delivery rollers 11 and 12 with which such machines are usually provided and which assist in drawing the sliver through the machine. These delivery rollers 11 and 12 are driven in any convenient manner by drive 70 mechanism forming part of the sliver-treating machine, the roller 11 being shown as mounted on a shaft 13 which is assumed to be so driven.

The sliver 10 is discharged into a can 80 15, embodying my invention, which can takes the place of the cans heretofore used for receiving such sliver. This can is mounted on a turn-table base 16 suitably mounted for rotation, as by having a pivot 85 stud 17 mounted in a bearing socket 18 set in the floor 19, as is clear from Fig. 6. The sides of the can are made of two cylindrical segments 20 and 21, which project upward from the edge of the base 16. The segment 90 20 is fixed on the base 16, in any suitable way, and the segment 21 is mounted on the segment 20 on vertical hinges 22 so that it may be swung to closed position as shown in Fig. 1 and in dotted lines in Fig. 7, to 95 form a complete cylindrical can, or to open position as shown in full lines in Fig. 7 to open the side of the can for half its circumference. The opposite edges of the segments 20 and 21 from those which are 100 hinged together by the hinges 22 are preferably arranged to overlap, as indicated in Figs. 1 and 7, and are provided with any suitable cooperating latch parts 23 for holding the segments in closed position. When 105 the segment 21 is in closed position, the sliver 10 may be coiled within the can; but when the segment 21 is swung open, the coiled sliver within the can may easily be 110 slid out laterally onto the floor 19 and dragged to any desired place without moving the can.

The base 16 and can 15 are driven in synchronism with the draw frame 9 or other associated sliver-treating machine. Such driving is conveniently obtained by a belt 5 which runs in a groove in the periphery of the base 16 and passes over idler pulleys 26 to a driving pulley 27 on any convenient moving shaft 28 of the draw frame 9. The pulley 27 is shown as on the sprocket shaft 28 of one of the drawing chains, though any other shaft may be used.

The sliver 10 is fed into the can 15 by my automatic feeding device. This is fundamentally a swinging chute 30, which is shaped much like a cupped human hand, and which is mounted to swing from side to side and up and down in synchronism with the draw frame 9. To this end, the swinging chute 30 is made of curved cross-section, to extend about half way around the sliver on its upper side, and is also curved longitudinally to direct the sliver downward, as is clear from Fig. 3. At its rear end the chute 30 is mounted by an upwardly projecting countersunk pivot bolt 31 to the lower end of a swivel cup 32 having a transverse hole 33 through it for receiving the horizontal finger 34 of a standard 35 suitably mounted in a cross bar 36 at the discharge end of the draw frame 9, the swivel cup 32 being held from longitudinal movement along the finger 34 in any suitable way, as by lying between a pair of cross-pins 37 projecting through such finger (Fig. 2). This makes a universal mounting for the rear end of the swinging chute 30, so that it can swing up and down around the axis of the finger 34 and can swing laterally around the axis of the pin 31.

Any suitable means may be provided for giving the chute 30 this double swinging movement, so that its free end will travel in a closed path. As shown, the chute 30 is provided on its upper surface at its free end with upwardly projecting eye 40, through which loosely projects a pin 41 on one end of an arm 42. Said arm near its other end projects slidably through a swivel member 43 transversely to the axis thereof, and such swivel member 43 is swiveled on the upper end of a rod 44 which is vertically adjustable to vary the height of the swivel member 43. The vertical adjustment of the rod 44 is conveniently obtained by having it project through aligned holes in the legs of a suitably supported U-shaped member 45, so that a spring-pressed shoe 46 on the end of a pin 47 projecting through the base of the U-shaped member 45 will bear against the side of the rod 44 between the two holes through which it passes and frictionally hold it in adjusted position. The lower end of the rod 44 is conveniently bent, as shown in Fig. 1, to provide an adjusting handle. This provides a vertically adjustable ful-

crum point in which the arm 42 both swings and slides. At an intermediate point the arm 42 has clamped thereon a downwardly extending finger 48, provided with a hole through which projects an eccentric pin 49 carried by a disk 50 on a shaft 51 suitably mounted in a bearing support 52 mounted on the cross bar 36. At its other end the shaft 51 carries a friction disk 53 with the face of which a friction roller 54 on the shaft 13 cooperates. The roller 54 is preferably adjustable axially of the shaft 13, as indicated in Fig. 2, by such adjustment producing different relative speeds of rotation of the shafts 13 and 51.

In operation: The rollers 11 and 12 discharge the sliver 10 beneath the swinging chute 30, which directs the sliver downward into the can 15. The chute 30 swings both on the axis of the finger 34 and on the axis 85 of the pivot bolt 31, so that its free end travels in a closed path to direct the sliver 10 into the can 15 in the form of a coil. This movement of the swinging chute 30 is produced by the action of the eccentric pin 49, the rotation of which both swings the arm 42 up and down with the swivel member 43 as a fulcrum and slides such arm 42 longitudinally back and forth in the swivel member 43. The swinging movement of the chute 30 is of such extent that it makes a sliver-coil of less diameter than the can 15, preferably about half such diameter, as is clear from Fig. 2. At the same time that the sliver is fed into the can 15, the can is 100 slowly rotated, so that for each turn or coil of the sliver the can makes a fraction of a revolution; so that as a result successive turns or coils of the sliver are not directly superposed, but instead are displaced circumferentially of the can. This makes a non-tangling coil. When the can 15 is full, the side segment 21 thereof may be swung open and the sliver-coil within the can may be dragged out of the can onto the floor 19, or onto a low truck, and slid on the floor or carried on the truck to the next machine or other desired place. Then the side segment 21 is closed again, and another coil or sliver 10 is fed into the same can.

I claim as my invention:

1. In combination with a sliver-treating machine, a can, and means for automatically guiding the sliver discharged from said machine into said can in a coil, the speed of said means being adjustable relative to the rate of discharge of the sliver to vary the size of the coil.
2. In combination with a sliver-treating machine, a can, means for automatically guiding the sliver discharged from said machine into said can in a coil, the speed of said means being adjustable relative to the rate of discharge of the sliver to vary the size of the coil, and means for rotating said

can slowly in relation to the coiling of the sliver to cause successive turns of the sliver-coil to be displaced circumferentially of the can.

5 3. In combination with a sliver-treating machine, a can, and means for automatically guiding the sliver discharged from said machine into said can in a coil of materially less diameter than the can, the speed of said 65
10 means being adjustable relative to the rate of discharge of the sliver to vary the size of the coil.

4. In combination with a sliver-treating machine, a can, and means for automatically 15
guiding the sliver discharged from said machine into said can in a coil of materially less diameter than the can and for causing successive turns of the sliver-coil to be displaced from one another circumferentially 20
20 of the can, the speed of said means being adjustable relative to the rate of discharge of the sliver to vary the size of the coil.

5. In combination with a sliver-treating machine, a can arranged to receive the sliver 25
discharged from said machine, said can having sides formed of relatively movable segments by the relative movement of which the can side may be opened to permit the lateral withdrawal of the sliver-coil, and means for 30
30 automatically feeding the sliver discharged from said machine into said can in a coil of materially less diameter than the can and for causing successive turns of the sliver-coil to be displaced from one another circumferentially of the can.

6. In combination with a sliver-treating machine, a can arranged to receive the sliver discharged from said machine, said can being provided with a side part which is movable 40
40 with respect to the remainder of the can to provide a lateral opening through which the sliver-coil may be withdrawn, and means for automatically feeding the sliver discharged from said machine into said can 45
45 in a coil of materially less diameter than the can and for causing successive turns of the sliver-coil to be displaced from one another circumferentially of the can.

7. In combination with a sliver-treating 50
machine, a can arranged to receive the sliver discharged from said machine, said can comprising a base and a plurality of side segments, said side segments being hinged together so that by swinging one segment outward a withdrawal opening is provided in the side of the can for the sliver coil, and means for automatically feeding the sliver discharged from said machine into said can 55
55 in a coil of materially less diameter than the can and for causing successive turns of the sliver-coil to be displaced from one another circumferentially of the can.

8. In combination with a sliver-treating machine, a feed chute against the under side

of which the sliver discharged from said machine is fed from the machine, said feed chute being provided with a swivel mounting to permit it to swing about two axes transverse to each other, and operating means for said chute for swinging it about 70
70 said axes so that an end thereof travels in a closed path.

9. In combination with a sliver-treating machine, a feed chute against the under side 75
of which the sliver discharged from said machine is fed from the machine, said feed chute being provided with a swivel mounting to permit it to swing about two axes transverse to each other, and operating means for said chute for swinging it about 80
80 both said axes.

10. In combination with a sliver-treating machine, a feed chute against the under side 85
of which the sliver discharged from said machine is fed from the machine, said feed chute being provided with a swivel mounting to permit it to swing about two axes transverse to each other, and operating means for said chute for swinging it about 90
90 said axes so that an end thereof travels in a closed path, and a can into which said chute directs said sliver in a succession of turns displaced from one another circumferentially of the can.

11. In combination with a sliver-treating 95
machine, a feed chute against the under side of which the sliver discharged from said machine is fed from the machine, said feed chute being provided with a swivel mounting to permit it to swing about two axes 100
100 transverse to each other, and operating means for said chute for swinging it about said axes so that an end thereof travels in a closed path, and a rotatable can driven at a speed slower than but proportional to the 105
105 swinging of said chute and into which said chute discharges said sliver.

12. In combination with a sliver-treating machine, a feed chute against the under side 110
of which the sliver discharged from said machine is fed from the machine, said feed chute being provided with a swivel mounting to permit it to swing about two axes transverse to each other, and operating 115
115 means for said chute for swinging it about said axes so that an end thereof travels in a closed path, and a rotatable can driven at a speed slower than but proportional to the swinging of said chute and into which said chute discharges said sliver, said can being 120
120 larger in diameter than the diameter of the coil into which said chute lays said sliver.

In witness whereof, I have hereunto set my hand at Indianapolis, Indiana, this 3rd day of February, A. D. one thousand nine 125
hundred and twenty-two.

JOHN W. GURLEY.
